Primary Examiner — Karen S Acker(74) *Attorney, Agent, or Firm* — Kilyk & Bowersox, P.L.L.C.; Todd M. Hess(57) **CLAIM**

The ornamental design for a nonwoven fabric, as shown and described.

DESCRIPTION

FIG. 1 is an isometric view of a nonwoven fabric showing my new design; and,

FIG. 2 is a top plan view thereof.

The design repeats uniformly throughout the surface of the nonwoven fabric. The claimed surface of the nonwoven fabric is flat and planar. The sides and rear of the nonwoven fabric form no part of the claimed design. The broken lines forming an edge surrounding the design represent the boundaries of the nonwoven fabric and form no part thereof.
